(57) CLAIM

The ornamental design for an athletic shoe attachment, as shown and described.

DESCRIPTION

FIG. 1 is a bottom perspective view of an athletic shoe attachment, showing our new design.

FIG. 2 is a side view of the athletic shoe attachment.

FIG. 3 is another side view of the athletic shoe attachment.

FIG. 4 is a front view of the athletic shoe attachment.

FIG. 5 is a rear view of the athletic shoe attachment.

FIG. 6 is a top view of the athletic shoe attachment; and,

FIG. 7 is a bottom view of the athletic shoe attachment.

The broken line showing is included for the purpose of illustrating environmental structure and forms no part of the claimed design.
